UNITED STATES PATENT OFFICE.

ERNST KÖRTING, OF KÖRTINGSDORF, GERMANY.

TWO-CYCLE MOTOR.

SPECIFICATION forming part of Letters Patent No. 781,889, dated February 7, 1905.

Application filed October 5, 1901. Serial No. 77,657.

To all whom it may concern:

Be it known that I, ERNST KÖRTING, a subject of the King of Prussia, Emperor of Germany, residing at Körtingsdorf, near Hanover, Kingdom of Prussia, German Empire, have invented new and useful Improvements in Two-Cycle Motors, of which the following is a specification.

The improvements according to this invention are intended to be applied to two-cycle motors in which the charge is supplied by separate air and gas pumps; and it consists in adapting the quantity of gas supplied to the power to be developed by providing in the gas-pump, between the compression-chamber and the end of the (pump) cylinder, a by-pass, the size of which can be altered by means of a closing device controlled by the governor. When the gas-pump is pumping, a portion of the gas already supplied is pumped out again, the quantity thus pumped back varying according as the by-pass is opened to a greater or less extent. The quantity of gas drawn in afresh and supplied during the next compression-stroke is varied accordingly, and the charge is thus rendered richer or poorer.

The accompanying drawings show diagrammatically the improvement according to this invention.

30 Figure 1 shows the arrangement of pumps and valve-gear for distributing air and gas for the double-acting two-cycle motor. Fig. 2 is a detail of a gas-pump with independent valves. Fig. 3 is a detail sectional view, on a smaller scale, showing the mixing-valve at one end of the power-cylinder.

z is the motor-cylinder, with piston-rod, connecting-rod, and crank.

l is the air-pump; *m*, the gas-pump, the pistons of both the pumps being mounted on the same rod *q*. The air-pump has an ordinary valve-gear, and the air is supplied to inlet-valves at each end of the motor-cylinder through pipes *o*. The gas-pump is also provided with a valve-gear in the form of piston-valves *f*, and the gas is supplied to the inlet-valves of the motor-cylinder through pipes *p*,

so that the air and the gas meet in the inlet-valve chamber or mixing-chamber and form the explosive mixture.

50

The peculiarity of the gas-pump is that its compression-chamber *a* is placed in communication with the back end *b* of the cylinder *m* by means of a passage *d*, closed by a valve *r*, the position of which, and consequently the 55 degree to which the said passage *d* is opened, is regulated by a system of levers *c*, controlled by the governor.

c is the suction-chamber of the pump.

When the motor is working, the air-pump 60 is always supplying, through the pipes *o*, the full quantity of air—i.e., the volume displaced by the piston—and always draws in from the outside a similar quantity of fresh air; but in the case of the gas-pump it is different. 65 When the gas-pump is pumping with the by-pass *d* opened to a greater or lesser extent, more or less gas is sucked back again from the compression-chamber *a* or pipe *p*, which is in communication with the pipe *o*, through 70 the chamber *n*, above the mixing-valve *n'*, so that in this case air is drawn from the pipe *o* into the pipe *p*. During the next compression-stroke the gas-pump delivers either the 75 whole or part of the volume displaced by the piston to the inlet-valve; but before this gas can reach the inlet-valve chamber through the pipe *p* it must replace the amount of gas or air previously pumped back—that is to say, 80 force back the air which entered the pipe *p*—so that in reality the amount of gas supplied to the driving-cylinder *z* through the inlet-valve will be less by the quantity pumped back during the suction-stroke, and consequently 85 the motor will develop correspondingly less power. As the pistons of both the air and gas pump always move through the same length, the relation of the quantity of air to that of the gas supplied in the same time always remains constant and equal to the relation between the pistons. As soon as during the 90 compression-stroke of the gas-pump the gas reaches the inlet-valve and begins to mix with the air entering at the same time the propor-

tion is the right one. The quality of the entering mixture remains, therefore, always the same. Only its quantity changes. The quantity of the entering air remains, on the contrary, constant, and until during the compression-stroke of the pump gas reaches the inlet-valve fresh air enters the motor-cylinder and then up to the end of the compression-stroke follows the explosive mixture.

10 In the modification shown in Fig. 2, *a* is the compression-chamber; *b*', the port leading to the cylinder end; *c*, suction-chamber; *d*, the by-pass with the valve *r*; *g*, the suction-valve; *h*, discharge-valve of the pump; *i*, an opening 15 in the center of the cylinder communicating with the suction-chamber. During the suction-stroke the suction-valve *g* is raised and the gas from the suction-chamber *c* enters the cylinder. As soon as the piston has passed 20 the opening *i* the gas enters the cylinder through this opening as well. During the next compression-stroke the gas is at first forced back again through the opening *i* until the piston has passed by it. Only after having 25 passed the opening *i*, the piston can force gas through the discharge-valve *h* into the compression-chamber *a*. When the by-pass *d* is closed, the gas-pump supplies at each stroke about fifty per cent. of its volume. If 30 the valve in the by-pass *d* is placed in a suitable position by the governor, the gas can flow back from the compression-chamber *a* during the whole of the suction-stroke, and during the first half of the compression-stroke this gas 35 will enter the pump-cylinder, so that a correspondingly smaller quantity will be drawn in through the suction-valve *g*. During the first portion of the compression-stroke the gas

would also escape back through the cylinder and the opening *i*.

What I claim, and desire to secure by Letters Patent of the United States, is—

1. In an internal-combustion engine, the combination with the working cylinder, of a pump for air, a pump for gas, a pressure-chamber connected with the cylinder of the gas-pump, a mixing-chamber connected with the working cylinder and the air-pump and said pressure-chamber, a valve for the admission of gas to the gas-pump, a by-pass between the end of the cylinder of the gas-pump and the pressure-chamber, and a throttling device located in the by-pass and controlled by the governor, substantially as described. 40

2. In an internal-combustion engine, the combination with the working cylinder, of a pump for air, a pump for gas, a pressure-chamber connected with the cylinder of the gas-pump, a mixing-chamber connected with the working cylinder and the air-pump and said pressure-chamber, independent suction and discharge valves for the admission of gas into the cylinder of the gas-pump and its discharge therefrom, a by-pass between the end of the cylinder of the gas-pump and the pressure-chamber, and a throttling device located in the by-pass and controlled by the governor, substantially as described. 50

In testimony whereof I have hereunto set my hand in presence of two subscribing witnesses. 60

ERNST KÖRTING.
